COUNTING DEVICE FOR PAPER MONEY

Curt Vogt, Berlin, Germany

Application February 3, 1932, Serial No. 590,709
In Germany October 18, 1931

4 Claims. (Cl. 93—93)

I have filed an application in Germany on October 18, 1931.

The invention relates to a device for keeping counts of paper money or similar objects in sheet form. In the counting off of a particular number of notes, the motor had hitherto to be brought to a standstill as soon as the last note of those to be counted off had passed the switch of the register. On account of the high speed of the motor it was necessary to brake the motor a certain time before the entry of the last note to be counted into the counting switch. In this, great difficulties were experienced. By means of this invention, these difficulties are not only overcome, but the stoppage of the motor is rendered superfluous.

According to this invention there is arranged in that part of the conveyor path of the notes situated in front of the counting gear switch, a deflector which in one extreme position permits the passage of the notes to the counting gear switch, but by means of the last of a particular number of notes which have closed the switch, is by electromagnetic means brought over into a position closing the passage for the following notes. An embodiment of the invention is shown in the accompanying drawing as an example. Fig. 1 is a longitudinal section through the casing of the conveyor taking the notes and carrying them to the counting gear switch, and Fig. 2 is a plan view of the apparatus according to the invention fitted in the casing, in one extreme position. Figures 3 and 4 show plan views of the same apparatus in two other positions.

The casing 1 contains revolving conveyor bands 2 of friction material, as for example rubber, which are carried over two belt pulleys 3 and 4 driven by a motor, and supply the notes to a stationary stripper 5 consisting of rubber or other friction material, with counter roller 6, which permit only one note at a time to pass through to the switch. Behind the stripper 5 there is arranged a pair of guide rollers 7, 7', and then an electric switch mechanism comprising a stationary contact piece 8 and a contact spring 8', which are arranged within a space between two pairs of discs 9 and 9' which press the note. The discs 9 are rotatably mounted on rods 27 adjustably arranged at the wall of the casing 1. This arrangement permits to displace the discs 9 into the position shown in Fig. 1 and to adjust them with respect to the conveyor path of the notes and in advance of the contact spring 8' for causing the notes to enter the bights of the discs capable of pulling the individual notes over the contact spring 8', which is thereby depressed by the notes

against the contact member 8 thus closing the circuit of the counting device. These discs convey the articles over said contact spring 8' to cause them to depress said spring against the said stationary contact member 8 for closing an electric circuit operating the register.

Between the stripper 5 and the switch 8, 8' is carried a flap 11 rotatable about an axis 10. The flap 11 can be so rotated that its lower part projects into the blocking position shown in broken lines in the conveyor passage passed by the notes. The flap 11 is switched over into the position shown in full lines when it is to leave open the conveyor passage for the notes to the switch 8. In this position the flap 11 is held by a latch 14 pivoted at 12 and loaded by a spring 13. The said latch engages with one end behind an arm 15 of the flap 11 and at its other end with a catch-pawl 16 as shown by Fig. 2.

The catch-pawl 16 is rotatably carried on the plate-shaped end 17 of a lever 18 pivoted at 19 and is actuated by a spring 20 which tends to keep the latch and the pawl in engagement. The lever 18 constitutes the armature of two electromagnets 21 which are connected in the current circuit 22 of a contact 23, the contact springs of which can be brought into the current closing position by a control cam 24 rotating with the number discs of the counting gear not shown. This position of the cam is shown in Fig. 3 and corresponds to the counting gear number which is brought into the visible position by the counting gear when the last note of the predetermined number of notes passes the counting switch 8. The cam 24 is preferably arranged on the corresponding number disc 25.

The magnet armature-lever 18 is actuated by a retracting spring 26 which tends to retract it into the position shown in Fig. 2 when the cam 24 has released the contact 23.

The method of operation of the apparatus is as follows: If, for example, 100 notes are to be counted off, the cam 24 is so positioned on the counting gear that it can close the contact 23 on the switching forward of the counting gear from the numeral position 99 on to the number 100. When this occurs, the current flowing in the circuit 22 energizes the electromagnets 21 which draw the armature 18 into the position shown in Fig. 3. Thereupon, the armature by means of the catch-pawl 16 rotates the latch 14 so that the latter releases the arm 15 of the flap 11 which now falls into the position shown in broken lines in Fig. 1. The catch-pawl 16 springs into the position shown in Fig. 3, in which a retaining por-

tion of the latch bears against the arm and a retaining portion of the catch-pawl bears against the latch which is hereby held in an extreme position.

5 Before a fresh counting-off of notes commences, the flap 11 is swung back by hand out of the position shown in Fig. 3 into the intermediate position shown in Fig. 4. Here the latch 14 engages behind the arm 15 and holds the flap 11, while the retaining portion of the catch-pawl 16 permits the latter to lock the latch 14. As soon as the next note on the conveyor path now liberated by the flap reaches the switch 8 and closes it, the cam 24 rotates in consequence of 10 the rotation of the counting gear in the direction of the arrow and opens the contact 23, so that the electromagnets 21 release the armature 18, which now springs back into the position shown in Fig. 2 and brings the catch-pawl 16 into engagement 15 with the latch 14 until the cam 24 has again come into the position shown in Fig. 3, whereupon the cycle recommences.

Having thus described my invention, I claim:

1. In a device for keeping counts of articles especially notes, the combination of a conveyor for the said articles with a switch mechanism arranged in the said conveyor path to be operated by said articles, an adjustable flap tiltably arranged over said path in front of said switch mechanism, an adjustable latch to arrest said flap in its position of rest outside the conveyor path, an electromagnetic mechanism controlled by said switch mechanism at the end of a predetermined number of articles to throw said latch 30 out of its position of rest for releasing said flap to deflect articles from said path at the end of a predetermined number of counts, and a retaining portion arranged at said latch to cooperate with said electromagnetic mechanism for retaining said latch out of engagement in an intermediate position of rest preceding to the restoration of the position of rest.

2. In a device for keeping counts of articles especially notes, the combination of means for feeding the individual articles, with a counting gear, an electrical switch contact associated with said counting gear and actuated by said articles, a deflector tiltably arranged in advance of said contact to be adjusted alternately into a normal position for the actuation of said switch contact by the passing articles and into a deflecting position for suspending said actuation, and electromagnetic means operated by said counting gear to tilt said deflector from its normal position into its deflecting position after a predetermined number of articles have passed.

3. In a device for keeping counts of articles especially notes, the combination of conveyor for the said articles, with a counting gear, a switch mechanism associated with said counting gear and arranged in the path of said conveyor to be actuated by said articles, a deflector tiltably arranged in advance of said switch mechanism, manipulative means for tilting the said deflector into its normal position for the actuation of said switch mechanism by the passing articles, and electromagnetic means operated by said counting gear to tilt said deflector into its deflecting position for suspending said actuation after a predetermined number of articles have passed.

4. In a device for keeping counts of articles especially notes, the combination of a conveyor for the said articles, with a counting gear, a switch mechanism arranged in the path of said conveyor to be operated by said articles, a deflector tiltably arranged in advance of said switch mechanism, a detent for retaining said deflector in its normal position outside the conveyor path, and electromagnetic means controlled by said switch mechanism to be operated at the end of a predetermined number of articles for retracting said detent out of engagement with said deflector to tilt for deflecting articles from said path.

CURT VOGT.
